UNITED STATES PATENT OFFICE.

GEORGE H. SCHAFER, OF STILES, PENNSYLVANIA, ASSIGNOR OF ONE-FOURTH TO JAMES LEIBY, OF STILES, PENNSYLVANIA.

CAR-COUPLING.

SPECIFICATION forming part of Letters Patent No. 767,770, dated August 16, 1904.

Application filed January 22, 1904. Serial No. 190,113. (No model.)

To all whom it may concern:

Be it known that I, GEORGE H. SCHAFER, a citizen of the United States, and a resident of Stiles, in the county of Lehigh and State of Pennsylvania, have invented certain new and useful Improvements in Car-Couplings, of which the following is a specification.

This invention relates to car-couplings, and more especially to the type of construction known as "vertical" couplers, one of the objects of the invention being to render more positive and efficient the operation of the latch or locking pin familiarly employed in this class of couplings.

15 A further object of the invention is to insure the easy "drawing" of the latch-pin irrespective of the degree of draft tension exerted on the jaw while in a coupled condition.

Other leading considerations connected with 20 the novel construction are the promotion of its automatic coupling capacity and its adaptability for ready and positive coupling with other types of vertical couplers, as well as with a draw-head of twin character.

25 Further important considerations are involved in the present improvements, as will hereinafter appear.

With all of the above purposes in view the invention comprehends the novel construction 30 and arrangements of parts clearly set forth in the subsequent detailed description and illustrated in the accompanying drawings, forming part of this specification, in which drawings—

35 Figure 1 is a perspective view of a draw-head embodying my invention, said draw-head being represented as being set to adapt it for automatic coupling with a suitable construction of companion draw-head. Fig. 2 is a 40 side view of the draw-head represented in Fig. 1. Fig. 3 is a plan view disclosing a pair of the novel draw-heads, the same being shown in their relative position immediately prior to their becoming automatically coupled.

45 Fig. 4 is a part-sectional and part-plan view illustrating a pair of the novel draw-heads in their coupled and locked relation. Fig. 5 is a detail front edge view of the coupling-jaw as it appears in Figs. 1 to 3, inclusive. Fig.

6 is a side and Fig. 7 is an edge view of the 50 latch-pin.

Similar reference characters are employed to designate corresponding parts in the several figures of the drawings wherein they occur.

55 While I have generally illustrated and described my improved car-coupler as coactive with another of twin construction, it will become manifest as this description progresses that one of my said couplers is capable of a wide range of service with numerous other constructions of couplers.

The improved coupler, or, as it is sometimes designated herein, the "draw-head," comprises the customary draw-bar A, integral 65 with which is the head A', which latter, as is frequent in constructions of the vertical-coupler type, has flat top and bottom surfaces, but possesses a vertical configuration of peculiar character, involving a main or body portion, 70 the sides a' a' of which divergently curve from the contiguous end of the bar A and merge at their front in inwardly-extending walls a² a², terminating in a longitudinally-disposed horizontal bearing A²; located to one side of the 75 axis of the draw-head.

The body of the head contains a horizontal recess A³, which opens through the wall a² and is of the contour generally indicated in Fig. 4. This recess opens laterally through 80 the forward portion of the side a' and through the wall a³, a slot a⁴ dividing the bearing into upper and lower sections and also intersecting the recess A³. Pivotaly mounted between the bearing-sections, near the outer ends thereof, is a horizontally-swinging jaw B, integral with which is a horizontal segment B' of the shape also more particularly indicated in Fig. 4, said segment being disposed substantially at a right angle to the jaw and extending with- 85 in the recess A³, where it presents an extended curved edge b, the contracted shank b' of this segment occupying a position permitting it to move within or from the slot a⁴ of the bearing. One of the reduced portions of the segment B' is notched to present an inclined shoulder b². 90

95 It will be observed by reference to Figs. 1,

2, and 5 that the jaw B is of somewhat flat character, thereby presenting opposite faces involving extended vertical as well as horizontal dimensions.

5 The top of the head A' contains a small longitudinally-extended rectangular opening, in which is guided the flat shank c of the latch-pin C, which includes a lower eccentrically-located stem c', circular in cross-section. The 10 eccentric location of this stem results in the shank presenting a shouldered part which has on one side a beveled portion c'', which extends vertically from the shouldered edge. When in position, the stem c' plays vertically 15 in a perforation therefor in the bottom of the head A', the pin being non-rotatively retained by the shank c and maintained in such position that when the pin is raised sufficiently high the segment B' can be swung from the 20 position indicated in Fig. 4 to that represented in Figs. 1 and 3, and thus occasion the curved edge portion b to move beneath the shoulder of the latch-pin and maintain the latter in an elevated position. (See Fig. 2.)

25 The contact of the jaw B with the bearing A² when said jaw is moved to the position represented in Fig. 1 will operate to limit the movement of the segment beneath the pin-shoulder, so that said segment when moving 30 in the direction indicated by the arrow in Fig. 3 will never assume such undue position as to result in its passing clear of the elevated pin and the latter permitted to drop. Therefore a coupler so conditioned will be unlatched 35 ready for automatic coupling with another coupler of the same or other suitable construction. Consequently upon the impact of the proper part of the coacting coupler with the projecting part of the segment the latter 40 will be swung within the recess A³ until its notched portion b² arrives beneath the shouldered part of the pin-shank, whereupon the pin will be permitted to drop, such shouldered part become engaged within the notch, 45 and the jaw B thus automatically moved to and locked in the coupled position. A perforation in the upper part of the pin-shank provides for a suitable operating connection, enabling the pin to be manually "drawn" when 50 required.

When both draw-heads of my improved construction approach each other in mutually-unlocked condition, the projecting part of the segment of each will serve to force back the 55 segment of the other, as indicated in Fig. 3, thereby throwing the jaws of both into engagement, in which position they are automatically locked, as may be gathered from Fig. 4.

60 In prior vertical-coupler constructions employing a latch-pin great difficulty has been

experienced in drawing the pin by reason of resistance exerted on the latter, due to draft tension on the jaw. In my construction this objection is overcome by reason of the mutually inclined or beveled faces of the pin and notched part of the segment, this arrangement 65 obviously permitting an easy relative movement of these parts irrespective of the draft tension.

70 Another notable advantage arising from my invention ensues by reason of the latching-pin having the lower stem c' playing in the bottom perforation, the pin being always properly guided throughout the range of its vertical movements.

75 I do not desire to be understood as limiting myself to the precise construction and arrangement of parts shown and described, but reserve the right to all modifications that may 80 be fairly within the scope of my invention.

Having now described my invention, what I claim as new, and desire to secure by Letters Patent, is—

1. In a car-coupling, the combination with a 85 recessed coupler-head having a top opening aligned with the draw-bar, and also with a forwardly-extending horizontal bearing at one side of the longitudinal center of the head, of a jaw provided with a segment having an extended inner portion with a horizontally-curved edge, a part of said segment having a notched extremity and adapted when the jaw is open to project beyond the head-recess, and another part of said segment adapted when 90 the jaw is closed to project at the outer side of the jaw-bearing and head, and a shouldered latch-pin playing in the top opening to ride on said curved inner part of the segment and descend for engaging the notched extremity 95 thereof when the segment is swung back and the jaw brought into an engaged position.

100 2. In a car-coupler, the combination with a recessed coupler-head having a horizontal bearing and an opening in the top, of a jaw provided with a segment adapted to swing within the head-recess and pivoted at the bearing, said segment having an engaging notch one surface of which is beveled, and a shouldered latch-pin playing in the top opening 105 having a beveled part for coacting with the notch-bevel, the shoulder of said pin adapted to ride on the segment and descend and bring its beveled part in bearing relation with the beveled surface of the segment-notch.

110 Signed at Coplay, in the county of Lehigh and State of Pennsylvania, this 13th day of January, A. D. 1904.

GEO. H. SCHAFER.
